(57) **CLAIM**

The ornamental design for a flower nylon headband as shown and described.

DESCRIPTION

FIG. 1 is a prospective view of the flower nylon headband, showing my new design;

FIG. 2 is a prospective view of the flower nylon headband in an unattached position;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The design incorporates nylon hair band, detachable gasket and artificial flowers so that a variety of artificial flowers can be used in one headband.

The shade lines in the Figures show contour and not surface ornamentation. The broken lines in the Figures show background, which form no part of the claimed design.
